(57) **CLAIM**

The ornamental design for a lighting fixture, as shown and described.

DESCRIPTION

FIG. 1 is a top perspective view of a first embodiment of the lighting fixture;

FIG. 2 is a bottom perspective view thereof;

FIG. 3 is a left side view thereof;

FIG. 4 is a front view thereof;

FIG. 5 is a right side view thereof;

FIG. 6 is a top view thereof; and

FIG. 7 is a bottom view thereof.

FIG. 8 is a top perspective view of a second embodiment of the lighting fixture;

FIG. 9 is a bottom perspective view thereof;

FIG. 10 is a left side view thereof;

FIG. 11 is a front view thereof;

FIG. 12 is a right side view thereof;

FIG. 13 is a top view thereof; and

FIG. 14 is a bottom view thereof.

FIG. 15 is a top perspective view of a third embodiment of the lighting fixture;

FIG. 16 is a bottom perspective view thereof;

FIG. 17 is a left side view thereof;

FIG. 18 is a front view thereof;

FIG. 19 is a right side view thereof;

FIG. 20 is a top view thereof; and,

FIG. 21 is a bottom view thereof.

Broken lines in the drawings represent features of the lighting fixture that form no part of the claimed design.

1 Claim, 10 Drawing Sheets
